Letters Patent. April Mar 22, 1809.

The schedule referred to in these Letters Patent and making part of the same containing a description in the words of the inventor Stevens, himself of his machine to color & finish silk &c &c &c

The machine consists first of ten front posts 9 ft high & 6 ft apart. 2¹/₂ of ten rear posts 4 ft high placed directly behind the front posts. 3¹/₂ of ten lower girdles 1¹/₂ to 2 long placed one foot high between the front and rear posts. 4¹/₂ of ten upper girdles 1¹/₂ to 2 long placed 2¹/₂ in. above the lower girdles. — 5¹/₂ of one front check 8 in. wide, and 56 ft long, which is moved backwards and forwards on the upper girdles by the screws 6¹/₂ of ten screws, which pass through the cog wheels and under rollers in the front post, to the front check to which they are confined. — 5¹/₂ of ten cog wheels which being turned on the screws move the front check to or from the rear check, to a distance corresponding with the width of the silk. The cog wheels are confined to the front posts by clamps, which take hold of washers confined to the back side of the wheels 8¹/₂ of one rear check, which is occasionally moved backwards and forwards on the upper girdles by a bar passing thru fullers and staples, in the under side of the check and in the heads of the rear posts. 9¹/₂ of one hundred & twelve caps one foot long & 16 inches wide, which are fastened with hinges on the upper side of the check.

Both checks have two rollers on their under side at each girdle. 4 bolts are fixed (as are all the the caps) on their inside with plated copper. Each cap has a brace confined at one end by a staple, near the edge opposite the hinge of the cap, and each brace has a concave foot piece; near the outer edge of the checks. 10¹/₂ of a cap piece placed on the tops of the front post, 56 ft long, leaving rollers in the center between the several posts — 11¹/₂ of a chain brace which revolves thru the whole machine under the several cog wheels and over the rollers next above them respectively above the cap piece. It is carried back by rollers in the tops of some of the front posts which are extended above the machine for that purpose each cog wheel has two handles opposite each other, in front by which, any wheel being turned the bar revolves and the whole ma

machine is put in motion. The wheel may be turned to the right or left by the power the front wheel is drawn forward by the latter it is forced backwards towards the rear wheel. Thus the checks are regulated at a distance proper for the reception of silk of any width. 12^{1/2} of a cradle way consisting of two slopes of plank or board, then set apart on the lower girder 56 feet long. 13^{1/2} of a cradle which moves along the way before hooks with a pair of tools for drying the silk. 14^{1/2} of a needle bar which rests upon the checks, at one end with small points to which the end of the silk is affixed 15^{1/2} of a small roller at the end of the machine opposite the needle bar, upon which the silk is wound from the reel. 16^{1/2} of a stay clasp which is a board 4^{1/2} long 9 1/4 in. wide, having several clasps 3 in. wide (squared like the caps) which are spaced and closed with screws. and 17^{1/2} of a reel with 3 wooden eyes and two copper heads, the inner hole is a screw with a twist on one end turning in one head, & with a crank on the other end which turns the screw, and thus moves the head next the crank to a distance from the other head equal to the width of the silk to be dyed. The other angles (placed as near the screw as they be on opposite sides) are square. They are confined in the head where the twist is, and pass thro' mortises in the head next the crank. The head next the crank slides on the two last mentioned arms. Each head has ten arms & 52 curved hooks on each arm, & may have any greater or lesser number.

In the use of the machine, the two corners at one end of the silk are applied to two iron hooks on opposite heads and opposite arms of the reel. Then the reel is turned and the silk affixed to hooks till the whole is wound up. Thus the silk is distended so as to have no wrinkles, and the dye stuff can circulate freely between the several laminae. Then the reel is suspended by one head into the dye stuff, it is plunged into cold water until sufficiently cleaned. Then it is stiffened with a composition of gum commonly used for that purpose, by pouring the composition upon the silk distended as above directed, or by plunging it in a vessel containing the composition.

Then the silk is removed from the reel on the smaller roller at the end of the machine opposite the needle bar. It is next taken from the roller & the end affixed to the needle bar, and spread along the machine upon the upper girder. The edges of the silk are then applied to the copper plates upon the checks, and confined there by raising and bracing the ends. Thus the silk is distended the whole length of the machine. Or if the web be not so long as the machine, the end is confined in the stay clasp, & that fastened by a line to either of the girders. Next by turning either of the cog

22

wheels to the right the front wheel is drawn forwards by the screw, till the silk is properly distended. The cradle is then moved slowly on the way with a pair of cables till the silk is perfectly dry. Then if the web be longer than the little, the dried part is wound into a cylinder placed behind the needle box, and turned with a crank & the remainder applied to the machine as before.
